OIL HEATING AND LUBRICATING DEVICE
FOR ENGINE CYLINDERS

Edward J. Doyle, Boston, Mass.

Application May 3, 1932, Serial No. 608,906

5 Claims. (Cl. 184—55)

This invention relates to devices for lubricating the internal parts of the cylinders and valves of steam engines and has particular reference to the lubrication of the cylinders of locomotives.

5 The internal parts of a locomotive cylinder are commonly lubricated by oil which is intermittently pumped under pressure through an orifice or spray head into the steam pipe leading to the steam chest of the engine cylinder. While it is common to heat the oil in the combined pump and oil reservoir in cold weather so that the oil will flow into the pump, it is general practice to force the cold oil into the cylinder. While this method of lubrication is common, it is not particularly efficient and masses of carbonized oil will be found in the cylinder when it is opened at the time of periodical inspection, thereby indicating that the oil was not thoroughly atomized in the spray head and distributed thoroughly throughout the steam 10 and also that an excessive amount of oil had to be used to insure lubrication of the relatively moving surfaces and to make up for the oil that did not reach these parts but was deposited where it could remain and become carbonized. Lubrica- 15 tion difficulties and carbon formation are particularly aggravated by the use of highly superheated steam because of the great difference between the temperature of the oil and that of the steam.

30 I have found that carbon formation can be largely prevented and the oil consumption reduced by heating the oil by the moving steam flowing to the cylinder, and approximately up to the temperature of the steam, before discharging 35 the oil through an orifice into the steam. This arrangement enables the oil to break up into small particles and to become distributed uniformly throughout the steam and constitutes an object of the present invention.

40 A further object of the invention is the provision of an oil injecting and heating device wherein the heating means for the oil is located within the steam pipe into which the oil is sprayed and is a part of the spray head.

45 Another object of the invention is the provision of an oil injecting and heating device that can take the place of the present spray head without any change in the oil piping system.

A further object of the invention is generally to 50 improve the construction and operation of engine lubricating devices.

Fig. 1 is a side elevation of a locomotive engine cylinder and a lubricating system therefor embodying the present invention.

55 Fig. 2 is a longitudinal section through the

steam pipe of Fig. 1 and illustrating in section the oil heating and spraying device embodying the present invention.

Fig. 3 is a partial plan view of the spraying device of Fig. 2.

Fig. 4 is a section taken along line 4—4 of Fig. 2.

Fig. 5 is an end view of the spraying device.

As here shown, the invention is applied to the cylinder 10 of a locomotive, which cylinder receives steam from a steam pipe 12 that admits the steam to a valve chest 14 having a valve therein which controls the flow of steam into the opposite ends of the engine cylinder. The cylinder lubricating system includes a spray head 16 which will be described in detail later and which is located in the steam pipe 12 and is connected through an oil pipe 18 with a terminal check 20 and from the terminal check through a pipe 22 to a combined oil reservoir and pump 24. The reservoir and pump 24 are more or less common in the art. The pump is mechanically operated and at each stroke of its piston forces a charge of oil through the terminal check and through and out of the spray head at a pressure that is greater than the maximum pressure of steam in the steam pipe. The spray head 16 is illustrated in longitudinal section in Fig. 2 and comprises an enlarged body 26 which has external screw threads 28 at its inner end by which the device is screw threaded into the side wall of the steam pipe 12. The body 26 is long enough to extend through the heat insulating packing 30 which encloses the steam pipe 12 and the outer end of the body is provided with a hexagonal or other shape of head 32 to which a wrench can be applied for screwing the body into the pipe. The body has a longitudinal oil passage 34 therein which opens into an internally screw threaded recess 36 in the head portion of the body and into which a coupling 38 for the pipe 18 is screw threaded. The particular manner in which the pipe 18 is connected with the body 26 and is placed in communication with the passage 34 is not herein of especial importance.

The inner end of the oil passages 34 of the body 26 is in communication in an enlarged longitudinal passage 40 in which one end of a long tubular member or pipe 42 is located. Said pipe is preferably brazed to the body 26 so that it is in effect integral therewith. The free end of the pipe or tubular member 42 is received within one end of a short tubular member 44 and is secured thereto in any suitable manner, preferably by welding material 46. The open remote end of the tubular

member 44 is closed by a removable screw plug 48 which can be removed when desirable to inspect and clean the internal passages of the device. The inner end of the plug 48 is terminated 5 a substantial distance from the end of the pipe 42, so that a chamber or passage 50 is formed between the confronting ends. The pipe 42 is provided with upper and lower longitudinal oil passages 52 and 54 respectively by a partition member or plate 56, which extends diametrically 10 across the pipe 42 and longitudinally thereof for the major portion of the length of the pipe and has the downwardly reflexed forward end 58 which is secured in an oil tight manner to the lower half of the pipe 42 whereby to form an oil tight closure for the end of the lower oil passage 54. Said partition member 56 is preferably 15 located in the pipe by severing the pipe longitudinally into complementary upper and lower sections, inserting the partition member between the two sections of the pipe and then welding the sections and partition member together by the application of lines of welding material 60 along the joints therebetween in the manner indicated 20 in Fig. 4. Preferably the partition member 56 has less width than the outside diameter of the pipe 42 so that there are grooves between the sections of the pipe beyond the side edges of the partition member that can be occupied by the 25 welding material. The lower portion of the pipe is provided with a series of orifices 62 which are arranged at divergent angles with respect to each other on opposite sides of the longitudinal line of the pipe 12 and communicate with the lower oil passage 54 in the pipe 42 so that oil is discharged from said orifices in different portions of the cross section of the steam pipe and at an angle to the steam flow so as to obtain good 30 distribution of the oil throughout the cross sectional area of the flowing steam.

The pipe 42 preferably extends diametrically across substantially the entire diameter of the steam pipe 12, or as close thereto as can be obtained in practice. Cold oil flows into the pipe 45 through the passage 34 in the body 26 and through the upper passage 52 in the pipe and thence through the passage 50 in the enlarged tubular end member 54 and thence in the reverse direction into the lower passage 54 from which it is sprayed 50 through the orifices 62. The oil hence is caused to flow substantially across the full diameter of the pipe and thence approximately halfway back before being sprayed out into the steam. As a result 55 of this arrangement, the oil flowing in the passage 52 is heated by the steam surrounding the pipe and thus becomes highly heated before it is forced through the spray orifices. The pump 24 is intermittent in operation and hence the oil in the passage 52 is periodically at rest so that there is ample 60 time for the oil to become highly heated. Since the highly heated oil is forced through the orifices under pressure, the oil becomes finely divided as it leaves the orifices and thus is caused to mix thoroughly and uniformly with the flowing steam in the steam pipe. The orifices 62 are disposed to 65 discharge the heated oil generally in the direction of flow of the steam and hence the orifices are directed down stream with respect to the steam flow. Thus the passage 52 is on the upper side 70 of the pipe where its side wall is impinged against by the steam and hence is in position to receive a large amount of heat from the steam.

The head 32 is provided with an indicating device 75 64 which is on the side of the head opposite the orifices and is intended to point up stream.

Thus an installer can properly install the device in the steam pipe and an inspector can readily observe the correctness of the installation.

While it has been proposed heretofore to heat the lubricating oil prior to its introduction into the steam, so far as I am aware, the heated oil has not been forcibly ejected into the steam under pressure through a restricted orifice and hence could not be broken down by its own pressure into finely divided particles and distributed uniformly throughout the flowing steam. Furthermore, the oil was not heated by the flowing steam into which the oil was discharged and hence could not be heated to the temperature of the steam. Hence, my invention represents an improvement over the prior art.

I claim:

1. An engine cylinder lubricating device comprising a long hollow member having screw threads at one end by which said member can be fixed within the steam pipe leading to the cylinder, said hollow member having an oil entrance and a separating plate extended longitudinally therein providing two longitudinal passages connected in series and through which the oil is caused to flow from said entrance in series in opposite directions and to become heated, and orifices communicating with the last passage through which heated oil is discharged from the device.

2. An engine cylinder lubricating device comprising a pipe having means securing it within a duct which conducts steam to an engine cylinder, means including a partition plate which extends lengthwise of said pipe and which separates it into two longitudinal passages which are isolated at one end of said pipe, a closure for the other end of said pipe which provides a communicating chamber between said passages, and means for admitting oil into the end of said pipe opposite said closure and into one of said passages, said pipe having orifices through its side wall which communicate with said other passage and through which oil heated in its traverse of said passages is discharged into the steam duct.

3. An engine cylinder lubricating device comprising a pipe having means securing it within a duct which conducts steam to an engine cylinder, said pipe having two complementary longitudinal sections, a partition plate located between said sections which separates said pipe into two longitudinal oil passages which are isolated at one end of said pipe, a tubular member on the other end of said pipe having a removable closure therefor which is spaced from the end of said pipe and provides a connecting chamber between said passages, one of said pipe sections having orifices through its side wall and disposed along the length thereof, and means to introduce oil into said pipe and one of said passages to traverse said passages in succession to said orifices.

4. An engine cylinder lubricating device comprising a body member having an oil passage therethrough, means at one end thereof for connection with the duct which conducts steam to an engine cylinder, and a tube extended beyond said connecting means which is adapted to be located within said duct, said tube having a longitudinal partition plate therein which separates the interior of the tube into two longitudinal passages which are isolated at the end adjacent said body member, a closure for the other end of said tube which provides a chamber connecting said passages in series, means for admitting oil into said body member and into said passages in series, said tube having orifices in its side wall

through which the oil in said last passage is discharged into the steam duct.

5. An engine cylinder lubricating device for injecting into the cylinder steam pipe, oil heated by the steam in said pipe, said device having means providing an oil duct having an entrance and outgoing and return sections, each outside the other, each separately having a wall exposed

for direct contact with the steam in the pipe, the outgoing section having such length as to extend approximately entirely across the steam pipe, the return section having orifices through which oil heated in its passage through the sections is forced. 80
